(57) **CLAIM**

The ornamental design for an implement for washing scalp, as shown and described.

DESCRIPTION

FIG. 1 is a perspective view of an implement for washing scalp;

FIG. 2 is a top plan view thereof;

FIG. 3 is a fragmentary enlarged view taken from FIG. 1;

FIG. 4 is an enlarged front view of a solid line portion shown in FIG. 3, a rear view being the same view thereof; and,

FIG. 5 is an enlarged left side view of a solid line portion shown in FIG. 3, the right side view being the same view thereof.

The broken lines in the drawings depict environmental subject matter only and form no part of the claimed design.
